BEARING

Charles R. Short, Clermont, Fla., assignor, by
mesne assignments, to General Motors Corpora-
tion, Detroit, Mich., a corporation of Dela-
ware

Original No. 1,819,272, dated August 18, 1931, Se-
rial No. 221,340, September 22, 1927. Applica-
tion for reissue December 16, 1939, Serial No.
309,650

14 Claims. (Cl. 218—10)

This invention relates to machine elements
having surfaces adapted to be placed in rubbing
contact with a relatively movable part, such as
a bearing for a shaft.

It has been heretofore found desirable to em-
ploy porous metallic material as a bearing sur-
face in elements of this character, and to secure
this porous metallic material to a backing or re-
inforcing member of denser metal, by means of
a metallic bond between the porous and denser
members, said bond alloying with the porous and
denser metals to securely attach said metals to-
gether. Under certain conditions as, for in-
stance, when the machine element becomes high-
ly heated, the bond may be wholly or partially
broken down due to a tendency of the porous
material to absorb the bonding material when
hot, thus permitting the porous bearing surface
to become loose.

It is the primary object of this invention to
provide a novel and improved machine element
of this character in which the porous metallic
bearing surface is securely attached to the rein-
forcing member in such a way that it will remain
so attached during all conditions of manufac-
ture and operation.

It is also a further object of this invention to
devise a novel method of making machine ele-
ments of the type described in which the bearing
surface is attached to the reinforcing mem-
ber in an improved manner.

With these objects in view, one feature of the
invention consists in the provision of a machine
element having a porous metallic bearing sur-
face, secured directly to a denser metal reinforc-
ing member, without the use of any intermediate
bonding material.

A further feature of the invention consists in
a method of making such a machine element in
which the step of attaching the porous bearing
surface to the denser metal back consists in heat-
ing the two metal elements to a high tempera-
ture while clamped together under pressure. The
invention also contemplates the heating of the
elements clamped together as described in a
liquid bath.

The invention further contemplates the heat-
ing of the elements while clamped together as
described, by means of an electric circuit to elec-
trically weld such elements together.

Further objects and advantages of the pres-
ent invention will be apparent from the follow-
ing description, reference being had to the ac-
companying drawing, wherein a preferred em-
bodiment of one form of the present inven-
tion is clearly shown.

In the drawing:

Fig. 1 is a plan view of a preferred form of
porous metallic plate.

Fig. 2 is an enlarged sectional view on the line
2—2 of Fig. 1.

Fig. 3 is a sectional view, largely diagrammatic,
of apparatus used to weld the porous metallic
plate to a reinforcing member, for example a
connecting rod.

Fig. 4 is an enlarged fragmentary section of a
connecting rod bearing formed according to this
invention.

In my copending applications, Serial Nos. 188,-
930, now matured into Patent No. 1,768,529, and
221,341, now matured into Patent No. 1,834,746,
and filed respectively May 5, 1927, and Septem-
ber 22, 1927, I have disclosed bearings having
a facing consisting of a thin sheet of porous
metallic material, secured to a reinforcing back-
ing of denser metal having a greater tensile
strength, and certain methods of making such
bearings. The porous metallic element employed
in such bearings has been either such an ele-
ment as described in the application of H. M.
Williams, Serial No. 582,550, filed August 17, 1922,
and now matured into Patent No. 1,642,347, or
such an element as described in my copending
application, Serial No. 221,341, filed September
22, 1927, Patent No. 1,834,746 above referred to.
The porous metallic element described in the
Williams application is of substantially the same
porosity throughout, while that disclosed in my
copending application is of laminated construc-
tion having layers which differ in degree of po-
rosity. The methods employed to make these
metallic elements form no part of this invention
and need not be described in detail herein.
Briefly, it may be said that the porous metallic
element disclosed in the Williams 1,642,347 is
made by briquetting together a mixture of metal
powders, together with graphite and a volatile
void forming substance such as salicylic acid.
The briquette is then sintered in a non-oxidizing
atmosphere for a sufficient period to complete

the desired alloying. One of the powdered metal mixtures includes:

	Parts
Copper	90
Tin	10
Graphite	6
Salicylic acid	2 to 4

Another material which incorporates lead therein may have a formula as follows:

	Parts
Copper	60
Tin	5
Lead	35
Graphite	6
Salicylic acid	4

The metal element disclosed in my copending application is made by adding a layer, principally copper or copper alloy to the porous metallic element disclosed in the Williams application.

In Fig. 1 of the drawing, is disclosed a metallic element 20 which is of novel and improved form to give the best results when bonded directly to the reinforcing member without use of an intermediate metal bond such as tin, which has been formerly employed in making bearings with a porous metallic facing. It has been found that when the porous metallic facing is secured directly to the denser metal backing, particularly by electrically welding as set forth hereinafter, better results are obtained if a portion only of the two contacting surfaces are bonded. The metal element 20 according to the present invention is formed with an embossed surface, having areas 21 projecting above the remaining surface of said metallic element. The element is embossed in any suitable manner, for example, by pressing with a die of proper shape to secure the desired formation. It will be understood also that the raised areas 21 may be formed from the body of the metallic element as the element itself is formed, or may be formed thereon at a subsequent operation. The projecting areas 21 are joined to a reinforcing member of denser metal in the manufacture of a bearing as later described.

The metallic element described may be of substantially the same degree of porosity throughout or may be an element having the laminated construction described in my copending application previously referred to. It is more desirable to use the laminated form of metallic element and form the projecting areas 21 on the less porous metallic layer, for the reason that the less porous layer has greater tensile strength than the more porous metallic layer, and when attached to the denser metal reinforcing member, a stronger bond is formed which will require a greater force to break it down, than if the more porous material were secured to the reinforcing member. As set forth previously and more fully explained later, a more desirable bond is secured when a metal element having an embossed surface is secured directly to its reinforcing back by welding or heating to high temperatures, but it will be understood that these methods of bonding are not limited to the use of the embossed element, and may be employed to attach two plane surfaces together also.

This invention contemplates the bonding of the element 20 to a denser metal reinforcing member by the application of heat. To secure a bond in this manner the element 20 and the reinforcing member are clamped together in any suitable manner under comparatively light pressure and are heated while so held to a tempera-

ture of 1525° to 1550° F. and are then quickly cooled. This temperature will depend on the materials used.

The clamped assembly may be heated in any desirable manner, and satisfactory results have been obtained when said assembly is heated in a bath of molten salts.

The porous material may be composed of copper and an alloy of copper and other substances. When the porous material is heated while held in contact with the denser metal backing to the temperature referred to, a part of this alloy of copper and other substances melts, but the specified temperature is less than the melting point of copper. On cooling the melted portion of the alloy forms a bond attaching the porous metal to its reinforcing body.

It is also within the scope of this invention to effect the joinder of a porous metallic element to a denser metal member by heating to high temperatures by means of an electric current to electrically weld the two elements together. In accordance with this method of bonding the two elements, the porous element is held against the member to which it is to be attached, with the projecting areas 21 in contact therewith. One conductor of an electric circuit is in electrical connection with the reinforcing member, while the other conductor of said circuit is in connection with an electrode which is brought into engagement with the exposed surface of the porous element.

In Fig. 3 is disclosed diagrammatically a suitable apparatus for effecting joinder of the two metallic elements by electric welding. The apparatus disclosed is designed to weld a porous metallic element of curved form to the curved surface of a connecting rod bearing. As disclosed a connecting rod 22 is supported on a supporting cradle 23 having a hole therein through which the rod extends. The cradle is pivoted at 24 so as to have a rocking movement. The porous element 20 is placed in the curved end of the rod 22, with the projecting surfaces 21 in contact with the surface of the connecting rod. An electrode 25 having a roller 26 adapted to engage the upper surface of the metallic element 20 is supported above such element and is adapted to be brought into engagement therewith by any suitable means so as to press the element 20 into engagement with the connecting rod with a moderate pressure. A conductor 27 constituting one branch of an electric circuit connects the electrode with a suitable source of electrical energy, while a conductor 28 connects the cradle 23 with such source of energy, a switch 29 being provided to make and break the circuit as desired.

When the electrode is in such position as to hold the element 20 against the adjacent surface of the connecting rod the switch is closed and the cradle is rocked to bring the roller 26 above the projections 21 successively. As the roller successively comes above the areas 21, a positive contact is established at such areas and they are welded to the rod 22. By using a metallic element having raised surfaces a higher temperature is possible at the contacting surfaces with a given current and a better weld is secured than if it be attempted to weld one plane element to another throughout their entire contacting areas.

While apparatus is shown for carrying out this method in the making of curved bearings only, it is obvious that said method can be employed in the manufacture of flat bearings. In making

such bearings, instead of using a pivoted cradle such as 23, a cradle having lateral movement with respect to the electrode 25 could be employed.

5 In Fig. 4 is disclosed a connecting rod assembly having a facing of porous material bonded to the steel rod. An element 28 is shown between the rod 22 and the cooperating crank shaft 30.

In Fig. 4, which is on an enlarged scale, it 10 will be seen that between the projections 24 are channels 31 which are formed when said projections are formed on the element 28. These projections will serve as oil channels for any oil 15 which comes in contact with the bearing, permitting any such oil to reach a considerable part of the bearing surface. Obviously such oil will be more readily absorbed than if the porous element 28 had a plane surface thereof secured to the reinforcing member, so that any oil reaching 20 the bearing would have to be absorbed by said element 28 through the ends thereof.

While the form of embodiment of the present invention as herein disclosed, constitutes a preferred form, it is to be understood that other 25 forms might be adopted, all coming within the scope of the claims which follow.

What is claimed is as follows:

1. In the method of making bearings for shafts and the like, the step of welding a preformed 30 porous metallic lining to a reinforcing member of denser metal which consists in holding said elements in direct contact and heating the said elements to a high temperature while so held.

2. In the method of making bearings for shafts and the like, the step of attaching a preformed 35 porous metallic facing consisting of a plurality of metals having different melting points to a reinforcing member of denser metal which consists in holding the two metallic elements in 40 direct contact and heating said elements while so held to a temperature intermediate the melting points of the different metals in said metallic facing, whereby said porous facing is welded directly to said reinforcing member.

45 3. The method of attaching a preformed bearing element having a porous metallic structure consisting of a mixture of metals to a reinforcing element of denser metal which consists in holding the said two elements in direct contact and heating said elements while so held to a degree sufficient to melt only the lower melting constituents of said metallic structure.

4. The method of attaching a preformed bearing element having a porous metallic structure 50 of bronze to a reinforcing member of ferrous metal which consists in holding said bronze and ferrous elements in direct contact and heating such elements while so held, to a temperature intermediate the melting points of the high and 55 low melting point constituents of said porous bronze structure.

5. In the method of making bearings for shafts and the like, the steps of attaching a preformed 60 porous metallic bearing lining to a denser metal reinforcing member which consists in holding the said elements in direct contact and electrically welding said lining to said reinforcing member by partially melting said porous lining.

6. In the method of forming bearings for shafts 65 and the like, the steps of attaching a porous metallic lining to a denser metal reinforcing member which consists in forming uniformly distributed raised areas on the back surface of the porous lining, pressing said back surface in 70 direct contact with said denser metal and heat-

ing the contacting areas of the two metal elements to weld said lining and reinforcing member together.

7. In the method of forming bearings for shafts and the like, the step of attaching a porous metallic lining to a denser metal reinforcing member which consists in forming substantially uniformly distributed raised areas on the back surface of the porous metal lining, pressing said back surface directly upon said reinforcing member and 10 electrically welding the contacting areas of the two metal elements progressively until all such areas are welded.

8. The process of making a composite machine element which includes the steps of providing a 15 backing member of ferrous metal, providing a porous facing composed of compressed powdered material consisting at least predominantly of high-melting-point metal and which is substantially free from iron-corroding gases and vapors 20 sorbed therein, said porous facing being formed by sintering the compressed powdered material in a controlled atmosphere; holding the facing with the surface thereof in firm contact with the surface of the backing member of the ferrous 25 metal and heating the facing and the backing member while so held to effect a direct weld between the ferrous metal of the backing member and the high-melting-point metal of the facing without fusion of the latter metal.

30 9. A process as claimed in claim 8 in which the provision of the porous facing substantially free from iron-corroding gases and vapors sorbed therein includes heating the porous facing of compressed powdered material sufficiently to 35 drive out of the facing substantially all iron-corroding gases and vapors sorbed therein before the facing is contacted with the backing member in the welding operation.

40 10. A process as claimed in claim 8 in which the porous facing member is provided by compressing powdered material composed predominantly of high-melting-point metal and containing also lead, tin and graphite.

45 11. A composite machine element comprising in combination a ferrous metal backing member and a facing thereon consisting of a porous body of condensed and coherent powdered material composed at least predominantly of high-melting-point metal, the backing member and the facing being united substantially throughout their mutually contacting surfaces by a direct weld substantially stronger than the facing body, said facing being formed by sintering condensed powdered material in a controlled atmosphere 50 so that the facing is substantially free from iron-corroding gases and vapors sorbed therein, and said backing member and said facing being united by holding the facing with a surface thereof in firm contact with a surface of the backing member, and heating the facing and backing member 55 while so held to effect said direct weld between the ferrous metal of the backing member and the high-melting-point metal of the facing without fusing the latter metal.

60 12. A composite machine element comprising in combination a ferrous metal backing member and a facing thereon consisting of a porous body of condensed and coherent powdered material composed at least predominantly of high-melting-point metal, the backing member and the facing being united substantially throughout their mutually contacting surfaces by a direct weld substantially stronger in shear parallel to the welded surfaces than the facing body, said 65

facing being formed by sintering condensed powdered material in a controlled atmosphere so that the facing is substantially free from iron-corroding gases and vapors sorbed therein, and 5 said backing member and said facing being united by holding the facing with a surface thereof in firm contact with a surface of the backing member, and heating the facing and backing member while so held to effect said direct weld 10 between the ferrous metal of the backing member and the high-melting-point metal of the facing without fusing the latter metal.

13. A composite machine element comprising in combination a ferrous metal backing member 15 and a facing thereon consisting of a porous body of condensed and coherent powdered material composed at least predominantly of high-melting-point metal, the backing member and the facing being united substantially throughout 20 their mutually contacting surfaces by a direct weld characterized by a substantially distinct line of demarcation between the backing member and the facing and by substantially greater strength than the facing body, said facing being formed 25 by sintering condensed powdered material in a controlled atmosphere so that the facing is substantially free from iron-corroding gases and vapors sorbed therein, and said backing member and said facing being united by holding the 30 facing with a surface thereof in firm contact with a surface of the backing member, and heating

the facing and backing member while so held to effect said direct weld between the ferrous metal of the backing member and the high-melting-point metal of the facing without fusing the latter metal. 5

14. A composite machine element comprising in combination a ferrous metal backing member and a facing thereon consisting of a porous body of condensed and coherent powdered material composed at least predominantly of high-melting-point metal, the backing member and the facing being united substantially through their 10 mutually contacting surfaces by a direct weld characterized by a substantially distinct line of demarcation between the backing member and the facing and by substantially greater strength 15 in shear parallel to the welded surfaces than the facing body, said facing being formed by sintering condensed powdered material in a controlled atmosphere so that the facing is substantially 20 free from iron-corroding gases and vapors sorbed therein, and said backing member and said facing being united by holding the facing with a surface thereof in firm contact with a surface of the backing member, and heating the facing and 25 backing member while so held to effect said direct weld between the ferrous metal of the backing member and the high-melting-point metal of the facing without fusing the latter metal. 25
